UNITED STATES PATENT OFFICE

132,860

DESIGN FOR A COMBINED HEARING AID AMPLIFIER AND BATTERY CASING

Christian A. Wolf, Van Nuys, Calif.

Application June 22, 1940, Serial No. 93,180

Term of patent 3½ years

To all whom it may concern:

Be it known that I, Christian A. Wolf, a citizen of the United States, residing at Van Nuys, in the county of Los Angeles and State of California, have invented a new, original, and ornamental Design for a Combined Hearing Aid Amplifier and Battery Casing, of which the following is a specification, reference being had to the accompanying drawing, forming part thereof.

Figure 1 is a front elevational view of a combined hearing aid amplifier and battery casing showing my new design; and

Figure 2 is a side elevational view of the same.
Figure 3 is an enlarged sectional view on the line 3—3 of Figure 1.

The left side of the device of Fig. 1 is plain and the rear of Fig. 1 is plain.

I claim:

The ornamental design for a combined hearing aid amplifier and battery casing, substantially as shown and described.

CHRISTIAN A. VOLF.
